his Attorney.

UNITED STATES PATENT OFFICE.

JACOB A. HYLE, OF PHILADELPHIA, PENNSYLVANIA, ASSIGNOR TO TRI-CITY STEEL COMPANY, OF CHICAGO, ILLINOIS, A CORPORATION OF DELAWARE.

METALLIC RAILWAY CROSSTIE.

Application filed October 11, 1922. Serial No. 593,748.

To all whom it may concern:

Be it known that I, JACOB A. HYLE, a citizen of the United States, residing at Philadelphia, in the county of Philadelphia and State of Pennsylvania, have invented 5 certain new and useful Improvements in Metallic Railway Crossties, of which the following is a specification.

This invention relates to an improved and 10 novel metallic railway cross tie especially adapted to be employed in connection with the road beds of steam and electric railways.

The prime object of the invention is to provide an economical, simple, safe, durable, 15 reliable and efficient railway cross tie, possessing the requisite strength to withstand all of the strains to which such ties are usually subjected when in use, and which is so constructed as to materially increase 20 the longevity of the same.

Another object of this invention is to furnish a metallic cross tie of a few parts in connection with wooden blocks, said 25 blocks forming a resilient support for the track rails, and at the same time creating a reliable insulation of the rails so that said track rails will reliably serve as efficient conductors in connection with the usual automatic railway electrical signaling systems.

30 Further objects of the invention are to so construct the metallic tie and wooden blocks, that the blocks may be readily and quickly removed and new blocks inserted or replaced by a single employee and without re- 35 moving the tie, or in any manner disturbing the position of the track rail or road ballast beneath the tie; to safely and securely fasten the wooden blocks upon the upper face of the base portion of the tie, with the

40 outer upright face of each block in contact with the inner face of and between the upright sides of the metallic tie, said block or blocks extending a suitable distance above the top of said metallic tie; to so secure the tie members that a drainage opening will be formed through the entire length of the tie and into the road bed, said opening also serving to secure the tie within the road bed by the road ballast which will accumulate 45

50 and become wedged within said opening; to provide means at each end of the tie, forming a part of said tie, adapted to prevent sidewise, endwise and skidding action of the metallic tie, and to provide means for 55 so tightly clamping the wooden block or

blocks between the upright members of the tie as to compress the fibres of the wooden blocks to such an extent as to prevent splitting of the block when the track rail securing spikes are driven therein and at the same 60 time prevent any vibratory or swinging movement of the wooden blocks when they shall have been fixedly secured to the said metallic tie.

The foregoing and such other objects as 65 may appear from the ensuing description are accomplished by the construction, arrangement, assembling, combination and location of the parts hereinafter more fully described, illustrated in the accompanying drawings and particularly pointed out in the claims appended hereto, it being understood that slight changes in the precise form, proportions and minor details of the construction may be resorted to without 70 departing from the spirit or sacrificing any 75 of the advantages of the invention.

In the accompanying drawings which form a part of the specification it will be seen that:

80 Figure 1 is a perspective view of the novel railway cross tie embodying my invention.

Figure 2 is an enlarged plan view of the same, and

85 Figure 3 is an end elevation of the metallic tie with the wooden blocks secured thereto.

Similar numerals of reference are employed to designate corresponding parts throughout the several figures of the drawings.

90 In the embodiment of my invention as illustrated, I provide a railway cross tie of suitable or desirable dimensions throughout its length and breadth, which may be 95 made of any suitable metallic material, being preferably formed of two pieces or members, each member being made from the standard L or right angle shaped sections of steel which are now universally used, 100 each piece or member consisting of a flat inwardly and laterally extended base portion 1, and an integral vertical outer member 2, said outer members forming the outer upright walls of the tie, said vertical members 2, extending the entire length of the tie, and each of said members being cut away on an incline from the point 3, at each end of the tie to a point 4 at or near the outer 105 end portion of the wooden block.

It will be seen that the track rails 5 are seated and rest upon the upper surface of a suitable metallic plate 6 seated upon the upper surface of the hard wood block or blocks 7, said block or blocks being clamped between the upright members 2, near each end of the tie, each of said blocks being formed with straight vertical faces, the lower surface of each block resting upon and in contact with the inner face of the base portion of the tie, while the upper portion of each block extends a suitable distance above the top edge of the upright members 2 of the tie in order to furnish safe and reliable insulation of the track rails from the cross tie. The size of the hardwood blocks is sufficient to furnish the requisite strength to support the track rails and retain the rail fastening means, such as spikes of the type usually employed in securing the track rails to the ordinary wooden tie, said spikes being usually driven into the wooden blocks with the head portion of each spike overlapping and in contact with the upper surface of the base portion of the track rail.

The wooden blocks employed in this connection are inexpensive, since one block or a plurality of blocks of different degrees of width may be tightly clamped between the upright members 2, thereby permitting the use of the ends of logs; the well preserved portions of cast off hardwood ties, and other small size pieces of wood which would ordinarily be classed as waste material, said wooden blocks being first preferably impregnated or saturated with crude oil, creosote, or any other suitable or desirable preservative preparation or solution to increase their durability and longevity.

The said blocks are each formed rectangular in cross-section and adapted to rest in contact with the base portion of the tie. The fastening means employed for rigidly and securely clamping the wooden block or blocks to the body portion of the metallic tie and in contact with its base and the inner face of its upright members 2 consists of two headed bolts 8 possessing the requisite strength, screw-threaded at one end thereof and two securing nuts 9, one of said nuts being fitted to the screw-threaded end portion of each bolt, said fastening means being adapted to fixedly and firmly secure one or a plurality of blocks at the same time to the cross tie, one or a plurality of blocks being located near each end portion of the tie. Each securing bolt 8 is passed through an opening formed through the block or blocks within the tie and an opening formed in each upright member 2, so that when the securing nuts 9 are adjusted tightly against the outer surface of the said upright member, the fibres of the wooden blocks will become so compressed between the upright members 2 as to prevent

the blocks from splitting when the rail fastening spikes are driven therein and will materially serve to prevent weather conditions from allowing the blocks to split, as will be readily understood,

In forming my metallic tie of two sections of angle plate steel it is important that the base portions be separated to form a suitable space between the two sections, said space forming a longitudinal opening 75 9' extending the entire length of the tie, thus forming a drainage for all moisture from the tie to the road bed beneath and thereby increasing the longevity of the metallic tie.

It will be seen that the upper portion of each of the upright members 2 is provided with a concaved recess or cut away portion 10 near each end of the tie, the major portion of said member being removed at the central part thereof at the point 11, so as to permit any suitable or desirable form of anti-rail creeper (not shown) to rest in contact with the outer face of the wooden block, thereby preventing any interference with the electrical signalling system, and at the same time serving to anchor the rails to resist any creeping tendency thereof when the rolling stock is travelling over the track rails.

It is a well known fact with railway officials and others familiar with the trough shape construction of railway ties that when the ties are filled with road ballast, the continuous vibrating or bouncing up and down movement of the ties during the rapid passage of the rolling stock over the track rails, especially when the ties are not solidly tamped, causes the ballast to be pitched or tossed out from each end portion of the ties 100 into the path of the road way and rolls down from the road bed, and this action is more apparent with the joint ties where they usually are subjected to greater vibration than the intermediate ties, and where the 110 joints are not properly tamped at all times. Hence to avoid and to practically eliminate such removal and disturbance of the road ballast, it will be perceived that the base portion of each metallic section of my improved metallic tie, from each outermost end portion to the outer end of the wooden blocks is bent downwardly almost at a right angle with respect to the remainder of the base portion, forming a depending extension 115 12 at each end portion of each metallic section, said extensions projecting into the road bed and forming a V-shape opening through the base of the tie at each end thereof to retain the ballast, while the depending extensions 12 form a wedge-shaped portion beneath the tie proper which portion is buried so as to firmly grip the road bed and serving to effectually resist any and all tendencies of the ties to 130

skid sidewise or endwise, and at the same time acting as a stay at each end of the tie to resist all pulling and pushing strain on the ends of the ties which usually cause a sliding movement or displacement of the ties.

It will be seen that the ties constructed in accordance with my invention are entirely filled with road ballast between the wooden blocks, and at the outer side of the said blocks, the weight of said ballast serving to materially assist in retaining the ties in their normal position and in connection with the depending extensions 12, and the drainage opening 9' through which the ballast and road bed becomes wedged, the ties are firmly held and effectively prevented from shifting their position when subjected to the usual heavy strains caused by the rolling stock passing over the track rails supported upon said ties.

Having thus described my invention what I claim and desire to secure by Letters Patent is:—

25 1. A metallic railway tie of the character described, comprising two right angle steel sections, each section being formed with an upright member and an inwardly extended base portion, blocks of hard wood disposed

between said sections near each end thereof, 30 means for firmly securing said blocks to said sections, a concave recessed portion formed in each upright member near each end thereof, and a depending extension formed from the base portion and extending from the 35 outer side of each of said blocks to the outer end of each section adapted to form a V-shape opening between said sections for the reception of road ballast, and to project into the road bed. 40

2. A metallic railway tie of the character described, comprising two right angle metal sections, each section being formed of an upright member and a laterally extended base portion, hard wood blocks disposed 45 between said sections, means for rigidly securing said blocks to the sections, and a depending extension formed from the base portion and extending from the outer side of each of said blocks to the outer end of 50 each section, said depending extensions being adapted to grip into the road bed to form an opening between said sections for the reception of road ballast, and forming a wedge shaped portion at each end of the 55 tie. 112

JACOB A. HYLE.
